M. G. FARMER,
Fire-Alarm Telegraph.

No. 23,060.

Patented Feb. 22, 1859.

UNITED STATES PATENT OFFICE.

MOSES G. FARMER, OF SALEM, MASSACHUSETTS, ASSIGNOR TO WM. F. CHANNING.

IMPROVED ELECTRO-MAGNETIC FIRE-ALARM APPARATUS.

Specification forming part of Letters Patent No. **23,060**, dated February 22, 1859.

To all whom it may concern:

Be it known that I, MOSES G. FARMER, of Salem, in the county of Essex in the State of Massachusetts, have invented a new and Improved Town Fire-Alarm System; and I do hereby declare that the following is a full and exact description thereof, reference being had to the accompanying drawing, and to the letters of reference marked thereon.

The nature of my improvement consists in combining two or more key-boards or fire-alarm strikers with one or more electro-telegraphic striking-machines or alarm apparatus in the same closed electric circuit or in dependent closed electric circuits within the area of a town or municipality.

To enable others skilled in the art to make and use my invention, I will proceed to describe its construction and operation.

In the fire-alarm telegraph now in operation in the cities of Boston and of St. Louis, for which Letters Patent were granted to me in connection with Wm. F. Channing, of Boston, on the 19th of May, 1857, and to which reference is here made, a "signal-circuit," so called, is employed to convey the information of a fire from any part of the area of a city to its central telegraphic station, where it is received by an operator. Another circuit, called an "alarm-circuit," connects the same central station with telegraphic striking or alarm machinery in the public-bell towers. At the center station is placed a district key-board or other apparatus connected with the alarm-circuit for the purpose of completing and breaking the circuit at suitable intervals, so as to strike a definite alarm upon the public bells. The operator with this machinery is enabled to receive information of the existence and locality of a fire by means of the signal-circuit, and then by an act of intelligence and volition to strike a corresponding definite alarm on the public bells in the bell-towers by means of the district key-board or other apparatus placed in the "alarm circuit," so called. This system requires the expense of a central office and of an operator always on the spot.

By my present improvement I dispense, in the case of smaller towns or cities, with the central office and unite the functions of both

the signal and alarm circuits in one fire-alarm circuit provided with suitable apparatus.

In the drawing the divisions I II III, colored respectively red, blue, and yellow, represent the ground plan of a town divided into three fire districts or wards.

The fire-alarm circuit consists of telegraph-wires supported on posts or buildings and duly insulated in the ordinary way. This is represented by the green lines *a a' a''*, continuous or dotted.

Three alarm-towers are represented by the blocks A A' A'', containing electro-magnets *b b' b''*, or their equivalents, which are included in the firm-alarm circuit *a a' a''*. These electro-magnets are here described and understood as forming part of my electro-magnetic escapement and apparatus, called "improvement in magnetic alarm-bells," for which Letters Patent of the United States were granted me May 4, 1852, or as forming part of any other suitable device for liberating alarm machinery in the alarm-towers A A A; but such apparatus or device must be arranged so as to work in a closed circuit.

It is well understood that the armature of an electro-magnet, in its reciprocating motion, is drawn toward or held to the magnet when the electric circuit is closed, and that it is drawn back from the magnet by the reacting power of a spring when the electric circuit is broken. In a closed-circuit arrangement those motions are accomplished by the reaction of the spring which in an open-circuit arrangement would be accomplished by the direct electro-magnetic force.

In my electro-magnetic escapement referred to above, in an open-circuit arrangement the weighted arm is tripped by the withdrawal of the armature by the direct force of an electro-magnet. In a closed-circuit arrangement, in an equivalent action, the weighted arm is tripped by the withdrawal of the armature from the electro-magnet by the reactive force of a spring when the circuit is interrupted. The two methods are equivalent; but I describe the closed-circuit arrangement here so that any person skilled in the art may construct the whole of my system from this specification and the references herein made.

Four district key-boards or strikers are represented in an elementary form at B C D E. These consist of closed-circuit wheels *c d e f*, on which springs *g* always bear, completing the fire-alarm circuit, except when one of the ivory segments *h i k l* passes under one of the springs *g* in the course of the revolution of the circuit-wheel, breaking the circuit at such times and giving an automatic signal, according to their number and arrangement. For instance, in a key-board two such circuit-wheels might be combined, on causing one of which to revolve the district number III might be automatically signalized, and on causing the other of which to revolve an arbitrary signal—such as I, II—might be automatically given, to signify that the fire was all out.

The circuit-wheels in the drawing are represented with weighted handles *m*, which keep them in such position that the circuit is always closed when they are at rest. The circuit-wheels can be revolved by the hand applied to the handles *m*; but for actual service the circuit-wheel is carried by clock-work with greater regularity than it can be moved by hand, and will be liberated by depressing a key.

The fire-alarm circuit is made to include the key-board E by connecting one wire, *a'*, of the circuit with the base of the spring *g* and the other wire, *a''*, of the circuit with the stud supporting the circuit-wheel *f*, and it is made to include the other key-boards in a similar way. It passes also through all the electro-magnets *b' b''* in the bell-towers and connects with the two poles *n o* of the battery, and thus makes a continuous communication or circuit through the battery and the bell-towers and key-board stations contained in the system.

The number of ivory segments on each circuit-wheel will correspond with the number of the ward or district of the town in which it is placed, or to the number designating the key-board itself if it is designed to strike that number on the bells.

In the drawing, the circuit-wheel *c* of the key-board B, placed in the red district, marked I, has one ivory segment, *h*. The circuit-wheels *d e* in the key-boards C' D, placed in the blue district, marked II, have each two ivory segments, *i k*. The circuit-wheel *f* of the key-board E, in the yellow district, marked III, has three ivory segments, *l l l*. Several such key-boards may be placed in the same fire-alarm circuit. They will ordinarily be placed inside of buildings, such as police-stations, apothecaries' shops, or perhaps alarm-towers.

The key-boards may be inclosed in a cast-iron box with a door which may be locked.

As an additional precaution against an accidental interruption of the circuit from imperfect contact between the circuit-wheel *d* and the spring *K*, the shutting of the door may be made to close the circuit by pressing a spring connected with one wire of the circuit against an insulated anvil connected with the other wire of the circuit.

A galvanic battery, F, or some other source of electricity, is included in some part of the circuit. It may be placed conveniently in one of the buildings used in the system, either as a key-board station or as an alarm-station, or as both. The battery F consists of a copper plate, *n*, and a zinc plate, *o*, excited by an interposed piece of cotton-flannel moistened with dilute acid.

In practical operation a form of constant galvanic battery will be used which will need attention only at considerable intervals of time, and a sufficient number of pairs will be used to overcome the resistance of the conductors of the circuit.

Having thus described the several parts of my improvement, I will now describe them in their mutual dependence and operation.

The battery F being placed in action, a closed circuit is established through the fire-alarm-circuit wires *a*, the weighted handles *m* keeping the circuit closed through the circuit-wheels *c d e f*. The electro-magnets *e e' e''* in the alarm-towers are thus permanently charged with magnetism while the system is at rest. An armature placed before the poles of each of the electro-magnets is thus permanently held near to or in contact with the electro-magnet while the circuit remains closed, and if such armatures are suitably connected with electro-magnetic-alarm machinery in each of the alarm-towers, such machinery will be held at rest while the circuit remains closed and attract their armatures, and thereby detain the alarm machinery from acting. If a fire occurs now in district III, near key-board E, the circuit-wheel *f* is set in motion by an authorized person. As the ivory segments *l l l* pass under the spring *g* the fire-alarm circuit is momentarily interrupted, the armatures in the alarm-towers are released, and the alarm machinery gives one signal for each interruption. If bells are used, the bells in the three towers A A' A'' each strike three blows and make a suitable interval between the series each time that the circuit-wheel *f* is revolved. A public alarm of district III is thus given instantaneously all over the town.

Instead of an electro-magnet, an armature in the alarm-stations, an axial bar moving in a coil, or any other equivalent electro-magnetic device may be used.

In the circuit-wheels *f* any non-conducting substance may replace the ivory segments, or segments may simply be cut out of the circuit-wheels at corresponding places, or any otherwise equivalent form of circuit-wheel used.

If a town is large, and it is desirable therefore to divide the fire-alarm circuit into two or more circuits, this can be done by making them mutually dependent, so that operating one will operate all the others. In this case there must be a battery in each circuit and a relay at the point of connection between two mutually-dependent circuits, constructed

so as to operate equally well both ways, in a manner similar to that for which Letters Patent of the United States were granted to me on 29th day of January, 1856.

What I claim as my invention, and desire to secure by Letters Patent, is—

The combination of two or more key-boards or fire-alarm strikers, constructed and operating substantially as described, with one or

more electro-telegraphic-alarm machines, in the same closed electric circuit or in dependent closed electric circuits by means of a mechanism that will make and break a circuit, as herein shown and described.

MOSES G. FARMER.
